Primary Examiner — Eric Goodman*Assistant Examiner* — Ryan Harvey(74) *Attorney, Agent, or Firm* — Luedeka Neely Group, P.C.(57) **CLAIM**

The ornamental design of a swim platform, as shown and described.

DESCRIPTION

FIG. 1 is a frontal perspective view of the swim platform of our new design;

FIG. 2 is a front plan view of the swim platform of our new design;

FIG. 3 is a front plan view of the swim platform of our new design;

FIG. 4 is a top plan view of the swim platform of our new design;

FIG. 5 is a bottom plan view of the swim platform of our new design;

FIG. 6 is a right side view of the swim platform of our new design;

FIG. 7 is a left side view of the swim platform of our new design;

FIG. 8 is a frontal perspective view of the swim platform of our new design; and,

FIG. 9 is a front plan view of the swim platform of our new design.

The broken line portions of the drawings are included for the purpose of illustrating unclaimed structure and form no part of the claimed design.
